UNITED STATES PATENT OFFICE.

CHARLES E. POTTER, OF ST. LOUIS, MISSOURI.

COMBINED ALARM AND SIGNAL FOR WET-PIPE SPRINKLER SYSTEMS.

1,182,205.

Specification of Letters Patent.

Patented May 9, 1916.

Application filed January 30, 1915. Serial No. 5,231.

To all whom it may concern:

Be it known that I, CHARLES E. POTTER, a citizen of the United States, residing at St. Louis, Missouri, have invented a certain new and useful Improvement in Combined Alarms and Signals for Wet-Pipe Sprinkler Systems, of which the following is a full, clear, and exact description, such as will enable others skilled in the art to which it appertains to make and use the same, reference being had to the accompanying drawings, forming part of this specification, in which—

Figure 1 is a diagrammatic view showing a device embodying my invention, applied for use in connection with a sprinkler system. Fig. 2 is an elevational view of the combined alarm and signal with the housing which incloses the same in section and partially broken away. Fig. 3 is a vertical section showing a spring-driven train of gearing and certain levers forming a part of my improved device. Fig. 4 is a detail section showing the diaphragm which is acted upon by the water pressure in the system. Fig. 5 is a plan view of the diaphragm and a segmental bearing ring which is positioned thereupon. Fig. 6 is an elevational view of parts of the actuating mechanism of my improved device. Fig. 7 is an elevational view of parts of certain of the wheels in the spring-driven train of gearing forming a part of my improved device.

My invention relates generally to automatic sprinkler and fire alarm systems, and more particularly to a device which will automatically transmit to a central station an alarm and signal whenever the equilibrium of the water pressure within the pipes of the system is disturbed by the opening of one or more of the sprinkler heads resulting from fire or accident and which action necessarily results in a lowering of the pressure in the system.

The particular form of device herein illustrated and described is particularly intended for use in what is commonly known as "wet pipe" systems, that is, systems wherein all of the distributing pipes are normally filled with water under pressure.

The principal object of my invention is to provide a comparatively simple inexpensive apparatus which may be conveniently and advantageously connected to one of the main supply pipes of the system and

which device will in the event of the opening of one or more adjacent sprinkler heads, transmit to the central station one or more signals which, in addition to giving the alarm, shows the approximate location of the open sprinkler head.

A further object of my invention is to provide a device of the character described with means for automatically transmitting to the central station a signal to show that the spring of the clock work or motor forming a part of the device is fully wound and that the device is properly set for use.

A further object of my invention is to provide certain details or features of improvement which will tend to increase the general efficiency and serviceability of an automatically released alarm and signal of the type to which my invention relates.

With the foregoing and other objects in view, my invention consists in certain novel features of construction and arrangement of parts, hereinafter more fully described and claimed.

Referring by numerals to the accompanying drawings, 10 designates one of the risers of the sprinkler system, 11 one of the lateral distributing pipes, the same carrying the usual automatic sprinkler heads, such as 12. Located in the riser 10 is an ordinary gate valve 13 and immediately above the same is the usual check valve 14.

My improved device is connected to the riser 10 at any desired point above the check valve 14, and as shown, the main body portion of said device is in the form of a plate 15 in which is formed a chamber 16 and connecting this chamber to the riser 10 is a suitable tubular connection 17.

Leading from the upper portion of the chamber 16 through the wall of the plate 15 is an air outlet 18, the same being normally closed by a suitable valve 19. Positioned on the plate 15 over the chamber 16 is a diaphragm 20, preferably of metal, the same being clamped to the plate 15 by a disk 21. This disk is attached to plate 15 by means of screws or in any suitable manner, and the central portion of said disk is extended upward as designated by 22 to form a housing over that portion of the diaphragm which overlies the chamber 16.

Connected to the center of diaphragm 20 is the lower end of a vertically disposed pin 23 which slides freely through the upper

portion of housing 22 and formed in said pin immediately above the diaphragm 22 is an annular groove 24.

5 Positioned on top of the diaphragm 20 and in the chamber within the housing 22 is a bearing ring 25 which is composed of a series of segments. The outer edges of all of these segments are provided with upwardly projecting ribs 26 which occupy corresponding bearings 27 formed in the underside of housing 22, and the inner edges of said segments are provided with ribs 26^a which engage in the annular groove 24.

10 Formed integral with or fixed to the disk 21 is a pair of upwardly projecting ears 28 and fulcrumed thereto, preferably by means of a knife-edged bearing 29, is one end of a horizontally disposed lever 30 which overlies the central portion of plate 15. The upper end of pin 23 engages against the underside of this lever 30, adjacent to its fulcrum point. Positioned on the lever 30 near the end opposite the end which is fulcrumed to the ears 28 is a weight 31 and pivotally connected to this end of said lever, preferably by means of a knife-edged bearing, is the lower end of a short vertically disposed link 32, the upper end of which is pivotally connected to a horizontally disposed lever 33 which overlies the lever 30. The end of lever 33 adjacent the point of pivotal connection to link 32 is fulcrumed preferably by means of a knife-edged bearing 34 to a short upright 35, the same being fixed to plate 15. The free end of lever 33 is provided with an upwardly projecting hook 36. The downward movement of lever 30 is limited by a stop 30^a which is seated in and projected upwardly from plate 15.

15 40 Fixed to plate 15 to the sides of levers 30 and 33 is a frame work 37, which carries a clock work or spring-driven train of gearing forming a part of my improved device, said frame comprising a pair of side plates which are framed together by suitable cross bars. Journaled in the side plates of this frame is a shaft 38 to which is fixed the inner end of a spiral spring 39, and the outer end of said spring is fixed to a cross piece 40 of the frame 37. One end of the shaft 38 projects beyond the frame 37 and said projecting end is made non-circular so as to receive the winding key. Fixed on this shaft 38 is a gear wheel 41, the same meshing with a pinion 42 which is loosely mounted on a shaft 43, the ends of the latter being journaled in the sides of frame 37. Fixed to pinion 42 is a ratchet wheel 44 having a single tooth or shoulder and adapted to engage therewith is a spring-pressed pawl 45, the same being carried by a gear wheel 46 which is fixed on shaft 43. Fixed on shaft 43 adjacent to the gear wheel 46 is a disk 47 in the edge of which is formed a notch 48. Positioned on lever 33 is an upwardly projecting finger 49

and projecting laterally from the upper end thereof is a pin 50, which is adapted to ride upon the periphery of disk 47 and to drop into the notch 48 therein. Gear wheel 46 meshes with a pinion 51 that is fixed on a shaft 52, the same being journaled in frame 37 and fixed on said last mentioned shaft is a gear wheel 53 which meshes with a pinion 54 on shaft 55. This last mentioned shaft is journaled in frame 37 and carries a gear wheel 56 which meshes with a pinion 57, the latter being fixed on shaft 58 which is journaled in frame 37. Fixed on this last mentioned shaft is a cross arm 59 provided with laterally projecting ends 60, the same being so adapted to engage the hook 36 on the end of lever 33.

20 25 30 Fixed on shaft 58 is a disk 61 provided with a single tooth or shoulder 62, the same being adapted to engage the laterally bent end 63 of a lever 64 which latter is fulcrumed at an intermediate point to a pin or bracket 65 which is fixed to frame 37. Journaled on a stud 66 which is seated in the rear one of the plates forming the frame 37 is a semi-circular plate 67 in which is formed an eccentric slot 68 and projecting therethrough is a pin 69 which is carried by lever 64. Formed in said plate 67 is a second eccentric slot 70, and projecting therethrough is a pin 71, the same being carried by an arm 72 which is fixed on a shaft 73. This last mentioned shaft is journaled in frame 37 and carries a short arm 74 from the outer end of which projects a pin 75, the same being adapted to engage on top of lever 33.

35 40 45 50 55 60 65 70 75 80 85 90 95 100 105 110 115 120 125 130 Fixed on shaft 38 which is immediately above stud 66 is a disk 76, the same being provided with a single tooth 77, the same being adapted to engage in either one of a pair of notches 78 which latter are formed in disk 67. The disk 76 is so located and of such size that its edge is adapted to engage the straight edges of the disk 67, thus limiting the movement of the latter in both directions, and when shaft 38 carrying disk 76 is rotated, the tooth 77 will engage in notches 78 and rotate disk 67 approximately a half revolution. Shaft 43 extends a short distance in front of the frame 37 and fixed thereon and insulated therefrom is a disk 79, the same being provided with a series of teeth 80 which are arranged in groups so as to be instrumental in sending a predetermined signal over the circuit in which the device is located, and which signal is registered at a central station. In the present instance I have shown this disk provided with teeth arranged in groups of four, one and two, and thus this box or station would be known as number 412, and in operation would send in a corresponding electric signal.

130 Fixed on the frame 37 above shaft 43 is a

bracket 81 in which is positioned a set screw 82 and fixed to and insulated from this bracket is a flat spring 83, the free end of which occupies a position beneath the screw 82 and said free end being bent downward to form a contact finger 84. Fixed to the underside of spring 83 is a contact plate 85 and fixed to the underside thereof is a second flat spring 86, the free end of which is positioned beneath the free end of spring 83 and said spring 86 being provided with a depending contact finger 87 which lies immediately adjacent to contact finger 84. Fixed to the underside of spring 86 and insulated therefrom is a contact plate 88, the same being provided with a contact point 89 which normally engages the free end of spring 86. Suitable electrical connections 90 lead from the contact plates 85 and 87 to a suitable indicator and recorder 91 located at a central station, and this circuit being provided with a suitable battery 92.

The operation of the device is as follows: Under normal conditions the pressure of the water in the distributing pipes acting against the underside of diaphragm 20 holds the same at its upward limit of movement, and consequently holds pin 23 elevated. The segmental bearing ring 25 is positioned on top of the diaphragm 20 and is instrumental in holding the same in its true position and causing pin 23 to operate in a straight line through its bearing. Without such bearing ring it has been found that the diaphragm tends to buckle while under pressure and such action affects the movement imparted to pin 23. The pressure of this pin against the underside of lever 30 holds the weighted end thereof at its upper limit of movement and by reason of the connecting link 32 the free end of lever 33 is held at its upper limit of movement with the hook 36 engaging one of the fingers 60 on cross piece 59. The engagement of the last mentioned parts holds the train of gearing in the housing 37 against movement, it being understood that said train of gearing normally tends to operate by reason of the power stored in spring 39, the same being normally wound.

It will be understood that in devices of this character, it is desirable that the central station be notified that the spring is wound and that the device is in condition for proper operation and to this end I have provided means for automatically transmitting a single signal to the central station when the spring has been completely wound.

Spring 39 is wound by the application of a proper key to the projecting end of shaft 38 and when the winding movement has been completed, disk 76 occupies the position seen in Fig. 3 with its periphery engaging the upper one of the straight edges of plate 76. When the last mentioned plate has been moved into this position pin 71

occupies the end of eccentric slot 70 which is nearest shaft 66 and as this movement takes place shaft 73 is rocked, thereby swinging the free end of arm 74 downward and causing pin 75 to bear downward upon lever 33, thereby releasing hook 37 from the engaged finger 60.

While lever 33 is elevated, pin 50 on plate 49 occupies notch 48 in disk 47 and when said lever is depressed by the downward movement of pin 75 pin 50 moves to a position below the periphery of disk 47. The train of gearing is now free to operate under the influence of the power stored in spring 39 and shaft 38 is rotated anti-clockwise, thereby imparting movement to disk 67 by the engagement of tooth 76 in one of the notches 78 and likewise rotary movement is imparted to shafts 43, 51, 55 and 58 through the various gears and pinions which are carried by said shafts. As soon as pin 71 moves a short distance through the angular end of slot 70, shaft 73 will be rocked to raise pin 75, but lever 33 will be prevented from moving upward by reason of the engagement of pin 50 against the edge of disk 47 until said disk has made a complete revolution. Thus shaft 43 upon which disk 47 is mounted, makes a complete revolution and the teeth 80 of disk 79 engage the contact fingers 84 and 87 in such a manner as to transmit through the circuit a single signal showing that the spring has been properly wound and that the device is in proper condition for operation. As soon as shaft 43 has completed its single rotation pin 50 will drop into notch 48, thus permitting hook 36 to reengage with one of the fingers 60, thus stopping and holding the train of gearing against further movement.

It will be understood that the free end of lever 33 is elevated by reason of the pressure of the water in the system against the underside of diaphragm 20 as hereinbefore described.

In case one or more of the sprinkler heads in that section of the system in which my improved device is located open by reason of heat from an adjacent fire or through accident, the release of water lowers the pressure in the system, thereby relieving pressure in diaphragm 20 and the weight on lever 30 will now cause said lever to drop and consequently permitting the free end of lever 33 to move downward. This action disengages hook 36 from engaged finger 60, thereby permitting the train of gearing to operate under the power stored in spring 39 and as gear wheel 41 carried by shaft 38 revolves motion is transmitted to shaft 43 by means of pinion 42 and said last mentioned shaft will be rotated several times or until shaft 39 has made approximately a complete turn at which time tooth 77 will pass from one notch 78 to the other, thereby causing disk

76 to make approximately a half revolution. As shaft 43 is rotated several times the teeth 80 will engage the fingers 84 and 87, thereby transmitting through the circuit to the central station repeated signals which indicate the opening of the sprinkler system. As the disk 76 completes its movement from one position to another, the pin 69 carried by lever 64 will move to the angular end of slot 68, thereby swinging said lever 64 so that finger 63 is brought into the path of travel of the single tooth or shoulder 62 on disk 61, and when such engagement takes place the movement of the train of gearing is stopped.

15 The circuit in which the device and the indicator at the central station are located is normally closed and as the teeth 80 carried by disk 79 pass the contact points 84 and 87, the circuit is broken by the engagement of the first tooth with contact finger 87, which movement raises spring 86 and breaking contact between said spring and contact point 89. Immediately after the tooth passes contact finger 87 the same drops 20 behind the tooth, thereby restoring contact between spring 86 and contact point 89, thus momentarily closing the circuit. Immediately after this action takes place the tooth engages contact finger 84, thereby raising 25 the same and the free end of spring 83, which action causes said spring to engage contact screw 82, carried by plate 81, thus momentarily grounding the circuit. After the passage of tooth beyond contact finger 30 84, spring 83 drops and the circuit is momentarily closed. These actions, namely, the breaking, the closing, and the grounding of the circuit, are repeated for each tooth 80 and by reason of the fact that the teeth are 35 arranged in groups a corresponding series of repeated signals in the shape of dots and dashes will be recorded by the register and indicator at the central station.

40 It will be understood that the operating parts of the device are inclosed in a suitable housing, the same being positioned on plate 15, as shown in Figs. 1 and 2.

45 A device of my improved construction is comparatively simple, is entirely automatic 50 in operation, transmits to the central station a signal to show that the operating spring is properly wound and that the device is set for use, and likewise transmits to the central station repeated signals to show that one or 55 more of the sprinkler heads of the system which is controlled by the device are open.

60 It will be readily understood that minor changes in the size, form and construction of the various parts of my improved device can be made and substituted for those herein shown and described, without departing from the spirit of my invention, the scope of which is set forth in the appended claims.

65 I claim:

1. The combination with a sprinkler sys-

tem and an electric circuit including an indicator, of a chamber in communication with the system, a diaphragm in said chamber, which diaphragm is normally under pressure of the water in the system, a normally wound clock-work, means acted upon by the diaphragm for normally holding the clock-work against movement, means adapted to be actuated by the clock-work for transmitting signals through the circuit, and means 70 coöperating with the clock-work and actuated by the winding movement imparted to the spring of said clock-work for effecting a limited movement of the signal transmitting means.

2. The combination with a sprinkler system and an electric circuit including an indicator, of a chamber in communication with the system, a diaphragm in said chamber, which diaphragm is normally under the 85 pressure of the water in the system, a normally wound clock-work, a weighted lever which is directly acted upon by the diaphragm, a second lever coöperating with the first lever and engaging a portion of the 90 clock-work to normally hold the same against operation, means adapted to be operated by the clock-work for transmitting signals through the circuit, and means coöperating with the clock-work and actuated by the winding movement imparted to the spring 95 of said clock-work for effecting a limited movement of the signal transmitting means.

3. The combination with a sprinkler system and an electric circuit including an indicator, of a chamber in communication with the system, a diaphragm in said chamber, which diaphragm is normally under pressure of the water in the system, a normally wound clock-work, means acted upon by the diaphragm for normally holding the clock-work against movement, means adapted to be operated by the clock-work for transmitting a series of repeated signals through the 100 circuit, and means arranged to operate automatically when the spring of the clock-work is wound and the device is set for use for effecting an operation of the signal transmitting means to transmit a single signal.

4. The combination with a sprinkler system and an electric circuit including an indicator, of a chamber in communication with the system, a diaphragm in said chamber, which diaphragm is normally under pressure of the water in the system, a normally wound clock-work, means acted upon by the diaphragm for normally holding the clock-work against movement, which means includes a weighted lever, means coöperating with and adapted to be automatically actuated by the clock-work for transmitting through the circuit a single signal when the spring forming a part of the clock-work has been completely wound, means for automatically stopping the clock-work after the 110 115 120 125 130

transmission of the single signal, and means whereby the signal producing means is operated to produce a series of repeated signals when the pressure of the water in the system is removed from the diaphragm.

5. The combination with a sprinkler system and an electric circuit including an indicator, of a diaphragm which is acted upon by the pressure of the water in the system, 10 a pin carried by said diaphragm, a segmental ring positioned on the side of the diaphragm opposite the side which receives the water pressure, said segmental ring coöperating with the pin carried by the diaphragm, a 15 train of spring-driven gearing, means adapted to be operated thereby for transmitting signals through the circuit, and means engaged by the pin on the diaphragm for normally holding the train of gearing against 20 movement.

6. The combination with a sprinkler system and signaling means, of a diaphragm which is acted upon by the pressure of the water in the system, a pin carried by said 25 diaphragm, a weighted lever engaged by said pin and coöperating with parts of the signaling means, and a segmental bearing ring positioned on the side of the diaphragm opposite to the side which is engaged by the 30 water pressure, which ring coöperates with said pin.

7. In an apparatus of the class described, a normally wound clock-work, means adapted to be actuated thereby for producing signals in an electric circuit, automatically operating means coöperating with the clock-work and signal producing means, for transmitting a single warning signal through the circuit when the clock-work is wound and 40 the device set for use, a member for normally holding the clock-work against operation, a member subject to the pressure of water in the system with which the device is associated, and means controlled by said 45 member for engaging a portion of the clock-work to normally hold the same against movement.

8. In an apparatus of the class described, a normally wound clock-work, means adapt-

ed to be actuated thereby for producing signals in an electric circuit, a member for normally holding the clock-work against operation, a member subject to the pressure of water in the system with which the device is associated, means controlled by said member for engaging a portion of the clock-work to normally hold the same against movement, and means for automatically effecting a release of the clock holding means to permit the clock-work to operate for a predetermined period of time immediately after the spring of the clock-work has been completely wound.

9. The combination with a sprinkler system and an electric circuit having an indicator, of a diaphragm movable under variations of the pressure of the water in the system, a normally wound signal transmitter coöperating with the electric circuit, means controlled by the diaphragm for normally holding the transmitting means against operation, and automatically operating means coöperating with the signal transmitter for effecting a temporary release of the holding means to permit a partial operation of the transmitting means to produce a warning signal through the circuit when said transmitting means is set for use.

10. The combination with a sprinkler system and a circuit provided with an indicator, of a spring-driven signaling device coöperating with the circuit, means controlled by the pressure of the water in the system for normally holding the spring-driven means against operation, and means adapted to release the holding means to permit a partial operation of the signaling means to produce a warning signal through the circuit when said signaling means is properly set for use.

In testimony whereof I hereunto affix my signature in the presence of two witnesses, this 28th day of January, 1915.

CHARLES E. POTTER.
